UNITED STATES PATENT OFFICE.

CHARLES P. KEELER, OF ATTLEBORO, MASSACHUSETTS, ASSIGNOR TO
MCRAE AND KEELER, OF ATTLEBORO, MASSACHUSETTS, A FIRM.

SAFETY ATTACHMENT FOR WATCH-FOBS.

SPECIFICATION forming part of Letters Patent No. 714,379, dated November 25, 1902.

Application filed March 24, 1902. Serial No. 99,735. (No model.)

To all whom it may concern:

Be it known that I, CHARLES P. KEELER, a citizen of the United States, residing at Attleboro, in the county of Bristol and State of Massachusetts, have invented a new and useful Improvement in Safety Attachments for Watch-Fobs, of which the following is a specification.

This invention has reference to an improvement in watch-fobs; and it consists in the peculiar and novel construction and the combination of the parts, more fully set forth hereinafter.

In carrying out my invention I interpose between the fob and the chain connected to the watch a plate provided with a pointed hook, which may be conveniently engaged with the material of the watch-pocket and hold the watch against accidental or unauthorized removal from the pocket.

Figure 1 is a front view of my improved safety attachment, the fob, and watch-chain. Fig. 2 is a sectional view of a watch-pocket, showing the fob secured in the pocket. Fig. 3 is a plan view of the blank out of which the preferred form of the safety attachment is formed. Fig. 4 is a sectional view of the preferred form of safety attachment.

In the drawings, *a* indicates the fob, which may be of any desired form or construction, and *b* a plate, having the end *b'* bent over to form a stop, which may rest on the edge of the pocket *c*, as is shown in Fig. 2, and is connected to the fob by the links *b²*. On the

lower end of the plate *b* is formed the upward-extending pointed hook *b³*, which when the plate *b* is pushed down into the pocket engages with the lining of the pocket to securely hold the plate against accidental or unauthorized removal. By this construction the plate *b* may, however, be readily removed by pushing the same downward to disengage the hook and swinging the hooked end of the plate inward from the lining of the pocket. 35 40

The plate *b* is provided with the parallel and elongated slots *b⁴*. The chain *d* is usually provided with the swivel *d'*, by which it may be connected with the watch. The opposite end of the chain is secured by the end link to the bar between the slots *b⁴ b⁴*, so that 50 the chain may slide on the bar.

Having thus described my invention, I claim as new and desire to secure by Letters Patent—

The combination with the plate *b* having the bent-over end *b'*, the pointed hook *b³*, and the slots *b⁴ b⁴*, of the fob *a*, the links *b²* connecting the fob and plate, and the chain *d* having one end thereof engaging with the bar between said slots *b⁴ b⁴*, as described. 55 60

In testimony whereof I have signed my name to this specification in the presence of two subscribing witnesses.

CHAS. P. KEELER.
